United States Patent Office.

JAMES A. FLEMING, OF SHAMBERG, PENNSYLVANIA.

Letters Patent No. 94,484, dated September 7, 1869.

IMPROVEMENT IN WRENCHES FOR ELEVATING PUMP-TUBES.

The Schedule referred to in these Letters Patent and making part of the same.

To all whom it may concern:

Be it known that I, JAMES A. FLEMING, of Shamburg, in the county of Venango, and State of Pennsylvania, have invented a new and useful Improvement in Swivel-Wrench and Clamp for Artesian Wells; and I do hereby declare the following to be a full, clear, and exact description thereof, reference being had to the accompanying drawing, making a part of this specification, in which—

Figure 1 is a side elevation of my improvement, showing the manner of slipping the wrench on to the rod.

Figure 2 is a side elevation of the same attached to the rod.

Figure 3 is an end view of fig. 1, showing the wrench-head and its attachment to the shank.

Figure 4 is a side view of the jointing-end of a rod.

Like letters of reference indicate like parts in each.

Heretofore, in putting in or removing the rods of oil and other deep wells, great difficulty has been experienced on account of the liability of the apparatus used, to let them slip and drop into the wells. This always involves a great loss of time and money to the operators, for they can only be recovered by grappling-irons and other instruments, and the use of these instruments in the contracted space of an oil-well is very tedious and vexatious.

By my invention, not only do I remove this serious difficulty, but am enabled to put in and take out the rods with great rapidity and ease; and

The nature of it consists of a shank having a swivel-head and two arms, between which swings a wrench-head, having a slotted aperture, the open end of which is closed by a lug, which is brought opposite to it.

To enable others skilled in the art to make and use my invention, I will proceed to describe its construction and manner of use.

a is the wrench-head.

b b are the arms of the shank *c*.

d is the swivel-head.

e are lugs, attached to one of the arms *b*.

f is the slotted aperture in the wrench.

g is a rod, such as is used in oil-wells.

The shank *c* of the rod *g*, fig. 4, is made square, for convenience in removing it.

If it is desired to remove the rods from an oil-well, the wrench is laid horizontally along the surface, so as to bring it at right angles with the end of the rod, which protrudes therefrom, and the slot *f* slipped on to the squared shank *c*. (The rod when in this posi-

tion is shown in red lines in fig. 1.) The shank *c* is then drawn up by means of a rope attached to the swivel-head *d*, until it reaches a perpendicular. (The wrench in this position is shown in fig. 2.) This throws one of the lugs, *e*, into the open end of the slot *f*, as shown in fig. 3, to secure the rod *g* effectually from all danger of slipping therefrom. The wrench is then hauled up by means of the rope attached to the swivel-head *d*, until the end of the next section appears above the surface.

A second wrench, of similar construction, is attached to this second section, in the manner hereinbefore described.

The swivel-head then being firmly held in position, the shank is rotated in it, so as to unscrew the section of rod, held by the wrench-head *a*, from the section held below by the second wrench. It is then let down by the rope; the shank swung around at right angles to the section, so as to throw the lug *e* from opposite the open end of the slot *f*, and allow the section to be removed from the wrench-head.

The second section is then drawn up by the second wrench and removed in like manner; the first wrench in the mean time, having been attached to a third section. This operation is repeated until all the rods are removed.

If, for any reason, the rope should break, there is no danger of the tubing or rods dropping into the well beyond reach, for the wrench-heads being wider than the mouth of the well, catch thereon, and are stopped in their descent.

The advantages of my invention are its safety and the great saving in time and labor which is accomplished by its use.

The wrench may be made of malleable iron, or other suitable material.

What I claim as my invention, and desire to secure by Letters Patent, is—

A swinging-wrench head, having a slotted aperture for the reception of a coupling-rod or tube, in combination with a lug, *e*, for closing such aperture and holding the rod in place while being raised or unjointed, substantially as above set forth.

In testimony whereof, I, the said JAMES A. FLEMING, have hereunto set my hand.

JAMES A. FLEMING.
